UNITED STATES PATENT OFFICE.

JAMES BUTLER, OF ST. CATHARINES, ONTARIO, CANADA.

REVOLVING DRAG-SCRAPER.

No. 841,929.

Specification of Letters Patent.

Patented Jan. 22, 1907.

Application filed May 16, 1906. Serial No. 317,248.

To all whom it may concern:

Be it known that I, JAMES BUTLER, contractor, of the city of St. Catharines, in the county of Welland, in the Province of Ontario, Canada, have invented certain new and useful Improvements in Revolving Drag-Scrapers, of which the following is the specification.

My invention relates to improvements in drag-scrapers; and the object of the invention is to devise a drag-scraper which may be dumped and restored to the operative position without the driver having to exert any appreciable force in dumping, and therefore effect an economy in both time and labor, and at the same time make the dumping easier for the team.

My invention consists of a scraper-body on each side of which are located two pins. One is placed centrally between the rear top of the scraper-body and the edge of the mouth, and the other is situated near the mouth of the scraper-body.

The scraper has two handles connected by two cross-bars, one placed near the ends of the handles and the other just clear of the back of the scraper-body. To this cross-bar is attached a device for holding the scraper body in the position of loading and dumping. The centrally-located pins act as pivots for the handles. These levers have two fingers at right angles to the handles, having lugs projecting inwardly therefrom. These act on bent portions of levers, which are connected inside the handles. At the front end of each of these levers is a jaw which is designed to straddle the forward pin when on the loading portion. To these levers is attached a bail to which the whiffletree is connected. The parts are otherwise arranged and connected in detail, as hereinafter more particularly explained.

Figure 1 is an elevation of the scraper in position for loading. Fig. 2 is a perspective view of the scraper ready for dumping. Fig. 3 is an elevation after being dumped. Fig. 4 is a detail of the levers. Fig. 5 is a sectional plan through the top of the lever, showing the key-slot.

In the drawings like letters represent corresponding parts in each figure.

A is the scraper-body, having two pins B located centrally between the rear upper back of the scraper-body and the front edge 55 of the mouth.

C represents two pins placed on the sides near the mouth of the scraper-body.

The handles D are connected to the scraper-body by means of the pins B, which act as pivots on which the handles turn. At 60 the front end of the handles D two fingers E E are formed at right angles to the inner sides. At the upper extremities of the fingers two lugs F F are attached, which act on a vertical projecting portion G of the lever 65 H. The levers H are located inside the handles D and are held in operative connection to each of the handles by pins B extending through slots I in the lever.

The front ends of the levers H are in the 70 shape of jaws J, which straddle the forward pin C when the scraper is in a loading position, as shown in Fig. 1.

In the forward ends of the levers H are formed key-slots K, by which the bail R is 75 attached, and the bail R has I-shaped inner ends which extend into the enlarged ends of the slots K and serve to hold the bail in the slots. The bail is provided with shoulders R' to hold the ends of the bail flush with the 80 inside face of the lever.

Just clear of the back of the scraper-body is a connecting cross-bar L, to which are fastened two spring-catches M M and also a double-way catch N. These three catches 85 act on a bar O of dovetail cross-section, fastened to the top of the back of the scraper-body A. The catch N is controlled by a rod P, which extends to a cross-bar Q, connected to the two handles D near the ends of the 90 same. The rod P is pivotally connected to the catch N and extends through an eye P', which extends downwardly from the cross-bar Q. A spiral spring P² extends between the eye P' and a pin on the rod and normally 95 exerts a forward pressure on the rod P.

When the scraper is in a loading position, as in Fig. 1, the catch N is caught and the handles D are rigid. When in this position, the handles D may be pressed down slightly, 100 so as to raise the mouth of the scraper-body A clear of the ground and prevent the scraper filling when being hauled by the team.

When the scraper is required to be dumped, the handles D are depressed. The lugs F F 105 press against the vertical projecting portion G of the lever H, and as the lever is free to move as far as the slot allows the levers H are released, and the line of draft of the team is changed from the pin C to the central pin B. 110

This line or draft makes the scraper-body A turn easier about the pin B, which is centrally located, than it would be about the pin C, thus allowing the load to be dumped without the driver having to exert any appreciable force. The two spring-catches M M catch on the bar O in this position and prevent the scraper-body A from revolving in the opposite direction. Therefore if the driver exerts a slight upward pressure on the handles D the scraper will dump and when dumped, as shown in Fig. 3, will be stopped from turning back by the spring-catches M M, which will catch the mouth of the scraper-body, and if the driver again exerts a slight upward pressure on the handles D the scraper-body A will press at the now bottom forward corner into the earth and complete the revolution, thus restoring the scraper to the loading position. The catches M M when the handles D are pressed upwardly will aid in starting this final movement, the catches springing past the edge of the mouth. The catch N will when the handles are brought high enough spring into position on the bar O. The lever will also drop back into place, and the scraper will again be in position for loading with the line of draft located at the pins C.

Although in this specification I have described the form of mechanism involved in my invention in detail, it will be understood that various changes may be made without departing from the spirit of my invention.

What I claim as my invention is—

1. In a drag-scraper the combination with the body, the handles, and means operated by the handles for changing the line of draft from a point near the mouth of the scraper to a central point.
2. In a drag-scraper the combination with the body having two pins located on the side of the scraper, one near the mouth of the scraper and the other centrally located between the mouth and the top of the back, of means operated by and connecting the han-

dles to the pins whereby the line of draft may be changed from the forward pin to the pin centrally located between the mouth and the top of the back of the scraper, as and for the purpose specified.

3. In a drag-scraper, the combination with the body provided with central and front pins and the handles swung on the pins and having at their lower ends projections at right angles provided with lugs on the inner faces of the same, levers having lock-jaws and provided with fingers projecting at right angles and coacting with the lugs of the projections, as and for the purpose specified.

4. In a drag-scraper the combination with the body, provided with central and front pins the handles swung on the pins and having at their lower ends projections at right angles provided with lugs on the inner faces of the same, of slotted levers having lock-jaws and provided with fingers projecting at right angles and coacting with the lugs of the projections of the handles, as and for the purpose specified.

5. In a drag-scraper the combination with the body provided with central and front pins, and handles, of levers connected to the body, by the centrally-located pins and provided with slots through which the centrally-located pins extend, and having jaw-shaped projections at the front ends to catch the forward pins, as and for the purpose specified.

6. In a drag-scraper the combination with the body and handles and levers connected to the same and provided with key-slots having enlarged openings at the inner ends, of the bails having L-shaped ends and shoulders adapted to abut the sides of the levers so as to make the L-shaped ends flush with the inner surfaces of the levers, as and for the purpose specified.

JAMES BUTLER.
